UNITED STATES PATENT OFFICE

FRANCIS S. INCO, OF LOS ANGELES, CALIFORNIA

AUTOMATICALLY-STABILIZED FOLDING BED

Application filed August 10, 1927. Serial No. 211,896.

This invention relates to folding beds and particularly to that type of folding bed in which the carriage is movable around the floor. In this type of folding bed it has been 5 regarded necessary to provide a carriage with an extensible brace which is extended when the main frame is swung into horizontal position, this extensible brace preventing the carriage from toppling.

10 It is an object of this invention to provide a folding bed in which the carriage will not topple when the main frame is being raised or lowered, and which has no extensible braces.

15 It is another object of this invention to provide a folding bed of the character mentioned in which the distribution of weight imposed on the carriage tends to maintain the carriage in proper upright position.

20 Other objects and advantages of the invention will be made evident in the following description.

The invention will refer to the accompanying drawings, in which—

25 Fig. 1 is a side view of a preferred form of the bed of my invention in upright or raised position.

Fig. 2 is a fragmentary section of one part 30 of the bed taken as indicated by the arrow 2 of Fig. 1.

Fig. 3 is a view similar to Fig. 1 but showing the main frame of the bed in lowered position.

Fig. 4 is a plan view of the head-end of 35 the bed taken as indicated by the arrow 4 of Fig. 3.

Fig. 5 is a fragmentary side elevational view of a modified form of the bed of my invention showing the bed frame in raised 40 position.

Fig. 6 is a side elevational view similar to Fig. 5 showing the bed frame in lowered position.

Referring to the drawings in detail, the 45 carriage 11 of the bed consists of end frames

12 and a cross-bar 13 which connects the end frames together. The end frames 12 have upper bars 14 and lower bars 15. Carried by the cross-bar 13 near each end frame 12 is a vertical post 16. The vertical posts 16 and 50 the upper bars 14 support main pivots 17.

The main frame 20 of the bed has main bars 21 which are pivotally supported on the main pivots 17. The main frame 20 includes the customary foot structure 23 and suitable 55 mattress supporting springs 24. Pivoted at 26 to the head-end of the main frame 20 is a head-piece 27 which is moved between the positions shown in Figs. 1 and 3.

Secured to the bars 14 and 15 of the end 60 frames 12 of the carriage 11 are rigid arms 29 to which primary levers 30 are pivoted by suitable pivot bolts 31. It should be noted that the pivot bolts 31 are positioned in front of and above the main pivots 17. The rear 65 ends of the primary levers 30 are pivoted by pivot bolts 32 to the head-piece 27 adjacent to the pivot bolt 26 which connects the head-piece to the main frame 20. The forward ends of the primary levers 30 are curved up- 70 ward as indicated at 34 and the forward ends thereof have links 35 pivotally connected thereto. Pivotally connected to the end frames 12 of the carriage 11 are secondary 75 levers 38. The pivotal connection is pro- 80 vided by pivot bolts 39 which are located at the extreme lower corners of the end frames. The secondary levers 38 extend forward to the front part of the end frames and are curved upward as represented at 40. The front ends 40 are pivotally connected, as 85 shown, to the lower ends of the links 35 which are also pivoted to the forward ends 34 of the primary levers 30. The primary and secondary levers 30 and 38 and the links 35 move 90 between the position shown in Figs. 1 and 3.

A primary tension means in the form of a series of tension springs 43 are connected to the bars 14 of the end frames 12, as indicated at 44, and to the secondary levers 38, 90

as indicated at 45. The purpose of these springs is to oppose the moving of the secondary levers from the position shown in Fig. 1 into the position shown in Fig. 3. The secondary tension means is provided in the form of tension springs 47 which are secured to fixed plates 48 attached to the front lower parts of the end frames 12. The upper ends of the tension springs 47 are connected by pivoted clips 50 to the primary levers 30 adjacent to the pivot bolts 31 and between the pivot bolts 31 and the pivot bolts 32.

When the main frame 20 of the bed is moved from raised position, as shown in Fig. 1, into lowered position, as shown in Fig. 2, the springs 43 resist the downward swinging of the secondary lever 38 and they are stretched so that as the secondary lever moves downward, the upward pull thereon is increased. It will be seen from the drawings that the opposing forces of the springs 43 tend to prevent the forward ends 34 of the primary levers 30 from swinging downward and consequently oppose the upward swinging of the rear ends of the primary levers 30 and the head end of the main frame 20. The springs 47 are also arranged to prevent an upward swinging of the rear ends of the primary levers 30 and of the head-end of the main frame 20. These springs consequently serve to counterbalance the main frame 20 when it is being raised or lowered so that the person accomplishing this act is not required to support any great portion of the weight of the main frame.

As previously pointed out, it has been necessary for all beds of the type of this invention to have extensible braces which are attached to the carriage and which are extended forward when the bed is being raised or lowered so as to brace the carriage in order to prevent it from toppling. In my invention the counterbalance springs 43 and 47 and the primary and secondary levers 30 and 40 are so designed and interconnected that the weights applied to the carriage are distributed when the bed is being lowered and will prevent the carriage from toppling. It will be seen that the most of the counterbalancing effect is accomplished by the primary springs 43. By pivoting the secondary levers 38 to the rear and lower parts of the end frames 12 and by connecting the springs 43 to the bars 14 and to the secondary levers 38 in back of the main pivot 17 which supports the main frame 20, the forces applied to the carriage for a stabilizing effect render an effect to cause the carriage to move from upright position.

Referring now to Figs. 5 and 6, I will describe a modified form 60 of the bed of my invention. The bed 60 includes a carriage 61 which is substantially identical with the carriage 11 of the preferred embodiment previously described. The carriage 61 has end frames 62 formed of an inverted U-shaped

piece of tubing, providing casters 63 and 64 which are connected by horizontal angle iron cross-bars 65 and 66. The end frames 62 are connected by a transverse angle iron bar 67 secured at its opposite ends to the horizontal cross-bars 66. Connected to the horizontal cross-bars 65 and 66 of each end frame 62 and extending a slight distance above the bar 65 is a vertical member 70. Pivotally connected at 72 to each end frame 62 at the juncture of the cross-bar 66 with the post 63 is a spring lever 74. Provided on each of the end frames 62 and attached at their opposite ends to the cross-bar 65 and the spring lever 74 thereof, are a series of coil springs 75.

Pivoted supported by the pivot bolts 76 upon the carriage 61 is a bed frame 77. Each of the bolts 76 passes through one of the cross-bars 65, which is clearly shown in Figs. 5 and 6, so that the bed frame 77 may have a vertical position, as shown in Fig. 5, or a horizontal position, as shown in Fig. 6. Pivotally provided on uprights 80 at the head-end of the bed frame 77 is a head frame 81 which is connected, by a link 82, to the upper end of the vertical member 70, on one of the end frames 62, so that when the bed frame 77 is in vertical position the head frame is folded, as shown in Fig. 5, and when the bed frame is disposed horizontally the head frame extends upward, as shown in Fig. 6. Rigidly secured to each of the uprights 80 is a diagonal brace 85 which has a hole intermediate its ends to receive one of the bolts 76, and has a curved arm 88 which extends upward and forward from this bolt. The end of each arm 88 and the arm of the corresponding spring lever 74 is connected by a link 89. The springs 75 constantly urge the levers 74 upward and as the links 89 connect the forward ends of these levers to corresponding lever arms 85; the springs 75 thus urge the bed frame 77 into the upward position in which it is shown in Fig. 5.

As the bed frame 77 is swung downward about the pivot bolts 76, the arms 85 are rotated with the bed frame about the pivot bolts 76 so that the links 89 force the spring levers downward and stretch the springs 75. This resists the downward movement of the bed frame 77 and supports the major portion of its weight so as to make it easy to operate the bed.

I believe my invention to be basically new in the provision of a folding bed of this character requiring no extensible braces or the sort for preventing the carriage from toppling. Consequently I do not wish to be limited to the exact form of the invention presented in this application since it is obvious that variations and modifications may be made without departing from the spirit and scope of the invention.

pivoting one end of said primary lever to said head-piece; means for connecting said primary lever to the free end of said secondary lever; primary tension means connected to said secondary lever and said carriage; and secondary tension means connected to said carriage and to said primary lever between the points where said primary lever is pivoted to said head-piece and said carriage.

¹⁰ In testimony whereof, I have hereunto set my hand at Los Angeles, California, this 4th day of August, 1927.

FRANCIS S. INCO.
